United States Patent Office.

CHARLTON EDEN, OF INDIANAPOLIS, INDIANA.

Letters Patent No. 96,091, dated October 26, 1869.

IMPROVEMENT IN MACHINES FOR MAKING ROPE-MOULDINGS.

The Schedule referred to in these Letters Patent and making part of the same.

To all whom it may concern:

Be it known that I, CHARLTON EDEN, of Indianapolis, in the county of Marion, and in the State of Indiana, have invented an Improved Circular Moulding-Machine; and I do hereby declare that the following is a full, clear, and exact description thereof, reference being had to the accompanying drawings, and to the letters and figures of reference marked thereon.

The nature of the invention consists in the construction of the machine hereinafter described, for the purpose of cutting straight an annular rope-moulding, said machine to be made of wood, iron, and steel, or any other suitable and convenient materials.

To enable others skilled in the art to make and use my said invention, I proceed to describe it more fully, as follows:

Figure 1, of the accompanying drawings, is a perspective view of said machine.

M N is a straight moulding, in the position in which it is cut by the said machine.

M' N' is an annular moulding, in a like position.

R is the rest, in which said mouldings are held while being cut.

T is the guide.

O, the cutter-shaft.

K K, the bearing in which it runs.

P, a pulley, for driving, and

Q, the cutter, whose edge is of the segmental circular form represented in section by Q, of Figure 3.

A B C D E F G H I is the frame on which the device sets, and is of the form there represented.

S is a slide, which moves up and down on A B, for the purpose of adjusting the size of the moulding to the position of the cutter.

The cutter reaches the moulding by passing into a notch, represented by Q' Q" Q, of Figure 2 of the accompanying drawings.

To use my said machine, the operator takes a cylindrical piece of wood, either straight or annular, of convenient size, and having properly adjusted the ma-

chine to it, presses it into the rest R until the cutter strikes it. It is then turned slowly, and pressed forward until it reaches the guide T, which, passing into the furrow made by the cutter, will, if the cylindrical piece of wood be turned slowly, by reason of its shape, (a segment of a female screw,) carry the wood so that the cutter will shape the furrow like the space of a round-threaded screw.

This may be repeated on another and another side, until the moulding is complete, making as many strands in the rope-moulding as may be desired. The cutter makes the adjacent sides of two adjacent strands each time the wood is run through.

By reason of the form of the frame A B C D E F G H I, one half of a cylindrical ring may be turned round and round in the rest R as conveniently as a straight cylinder.

The guide T, which is a segment of a female screw, may be either right or left-handed. If it be right-handed, the wood is turned to the right, and a right-handed moulding produced. If it be left-handed, the wood is turned to the left, and a left-handed moulding produced. A cutter may be placed on either end of the shaft O, and the same effect produced.

What I claim, and desire to secure by Letters Patent, is—

1. The combination of the rest R, the guide T, the bearing K K, the shaft O, and the pulley P, when the same are combined and used for the purpose of cutting rope-moulding, substantially as herein set forth.

2. The combination of the rest R and guide T with the cutter Q, substantially as herein set forth.

3. The combination of the rest R, the slide S, and the guide T, substantially as herein set forth.

In testimony that I claim the foregoing specification, I have hereunto set my hand, this day of May, 1869.

CHARLTON EDEN.
